PISTON FOR FUEL INJECTION PUMPS

William E. Leibing, Redwood City, Calif.

Application June 9, 1954, Serial No. 435,481

2 Claims. (Cl. 309—12)

My invention relates to pistons for fuel injection pumps and method of manufacture, and is a continuation-in-part of my copending application Serial No. 348,067, filed April 10, 1953, Patent No. 2,725,861, issued December 6, 1955, for Injection Fuel Pump for Internal Combustion Engines.

Fuel injection pumps are required to deliver extremely small quantities of fuel in extremely accurate amounts. To accomplish this by means of a piston and cylinder, not only must there be an extremely close fit between the piston and cylinder, but also the running clearances between a group of pistons and their cylinders must be extremely uniform. This has required the maintenance of almost impossibly close manufacturing tolerances, for example, in the range of plus or minus five hundred thousandths (.00005) for a nominally one-half inch piston and cylinder.

It is a primary object of my invention to provide a pump and method of manufacture wherein the piston and cylinder may be manufactured with tolerances which can be readily maintained, and in the course of assembly the dimensions of the piston may be altered to establish the necessary close tolerance running fit with its mating piston; further, whereby a high degree of uniformity may be maintained without expensive manufacturing procedures of the mating parts; and whereby in a multiple piston pump the clearances may be exactly mated even though the cylinder diameters should vary.

A further object of my invention is to provide a simple and effective means and method of altering the piston diameter, which is applicable not only in the initial manufacture of the fuel injection pump but also in effecting repair after the pump has worn.

With the above and other objects in view, as may appear hereinafter, reference is directed to the accompanying drawings, in which:

Figure 1 is a fragmentary partial sectional, partial elevational view of a fuel injection pump, incorporating my piston;

Fig. 3 is a similar longitudinal, sectional view of a modified form of a piston with the surrounding cylinder shown fragmentarily;

Fig. 4 is a partial sectional, partial elevational view of the partially prepared piston blank;

Fig. 5 is an elevational view of the expander member;

Fig. 6 is a partial sectional, partial elevational view, showing the expander member in its preliminary inserted position; and

Fig. 7 is a similar view, showing the expander in its final position, before trimming the end of the expander and piston.

Reference is first directed to Fig. 1, which illustrates a type of fuel pump disclosed more completely in my Patent 2,725,861.

The fuel injection pump designated 1 includes a cylinder block 2 having a ring of parallel cylinders. Each cylinder is provided with a liner 3. Each cylinder receives a piston 4 having a cap 5, forming a socket to

2

receive the end of a connecting rod 6. The connecting rods are connected to suitably oscillating mechanism, such as a wobble plate or other means, for effecting reciprocation of the pistons.

One end of the cylinder block 2 is provided with a discharge manifold 7, shown fragmentarily in Fig. 1. The discharge manifold is provided with a series of discharge valves 8, registering with corresponding cylinders.

Located within the cylinder block 2 and within the ring of cylinders is a float chamber 9 in which is mounted a float 10, disclosed in more detail in my copending application. The float controls inlet passages 11 which radiate to the ring of cylinders. Each liner 3 is provided with an inlet slit 12 communicating with a corresponding inlet passage.

Another type of fuel injection pump involves a plurality of cylinders 13 having a counterbore 14 at one end. Each receives a piston 15 on which is fitted a collar 16 retained by a spring clip retaining ring 17. A return spring 18 disposed between the collar 16 and base of the counterbore 14 tends to maintain the piston 15 in a raised position relative to its cylinder 13. The end of the piston 15 is fitted with a bearing button 19 adapted to be engaged by suitable means for depressing the piston.

The pistons 4 and 15 are essentially identical in that each one is provided with a tapered bore 20 and a constricted aperture 21 at its head end. In the case of the piston 4, the aperture 21 intersects a socket cooperating with the cap 5 to retain the end of the connecting rod 6. In the case of the piston 15, the aperture 21 receives a stem for retaining the bearing button 19. The tapered bores 20 of the pistons 4 and 15 receive a tapered expander plug 22, the position of which in the tapered bore 20 determines the diameter of the piston.

In order for a fuel injection pump to operate satisfactorily, it is necessary that each piston and its cylinder deliver an accurate and relatively minute amount of fluid. This necessitates an extremely uniform fit between the pistons and their respective cylinders or liners, as the case may be. Heretofore, this has been accomplished by expensive finishing operations in which it is necessary to hold the tolerances of the piston and cylinder to plus or minus five hundred thousandths (.00005). Not only is such accurate manufacturing expensive, by reason of the time and care required, but at best the percentage of rejection is extremely large. On the other hand, the manufacture of the cylinders or their liners to a tolerance plus or minus one-half a thousandth (.0005) is well within standard manufacturing techniques at only a small fraction of the cost for a higher order of tolerance.

My piston is primarily designed so that its diameter may be varied minutely, in order that each piston may be individually fitted to a corresponding cylinder or liner without requiring excessively close tolerances in the manufacture of the piston itself.

My method of manufacturing the piston is best illustrated with reference to Figs. 4 through 7. The piston blank is machined from bar stock, its tapered bore 20 and aperture 21 drilled, and then externally threaded or grooved, to form a rough blank of the pistons 4 or 15, as the case may be. A tapered expander plug 22 is then formed and is initially somewhat longer than the internally tapered skirt of the piston. It has been found satisfactory to employ a taper for the bore 20 and expander plug 22 of one-fourth inch ($\frac{1}{4}$ ") per foot. However, a lesser taper of one-eighth inch ($\frac{1}{8}$ ") per foot may be used. The taper should be such that once in place the expander plug will not vibrate loose.

The expander plug 22 is inserted in its piston and forced therein sufficiently to expand the piston approximately one-thousandth to two-thousandths of an inch (.001" to .002"). The piston is then center-less ground,

maintaining a tolerance of plus or minus one-half thousandth (.0005). The piston is then trial inserted in its corresponding cylinder or liner and the clearance determined. One method of accomplishing this is by use of a conventional air measuring device which measures the leakage of air past the piston. Such a device is capable of indicating clearance in terms of a millionth of an inch.

After observing the clearance and noting whether the piston is too loose or too tight, the expander plug is then forced axially a trial distance and the piston reinserted. This inherently is comparatively a rapid and dependable operation, resulting in a remarkably uniform fit between a series of pistons and their cylinders. After the piston has been fitted, the excess end of its skirt and the protruding end of the expander plug are trimmed off.

The piston expands uniformly, both axially and circumferentially, and the amount of needed expansion is well within the elastic limit of most materials, for example, stainless steel or aluminum bronze, so that should the fit be too tight, requiring retraction of the expansion plug, the piston contracts into conformity therewith.

Having fully described my invention, it is to be understood that I do not wish to be limited to the details herein set forth but my invention is of the full scope of the appended claims.

I claim:

1. A piston construction, comprising: a piston having an axially apertured head at one end and an internally tapered skirt extending therefrom, open at its extremity; and an expansion plug fitting said skirt, and accessible through said apertured head and the open end of said skirt for axial movement, to expand and permit radial contraction of said skirt.
2. A piston construction as set forth in claim 1, where in: the taper of said skirt and said plug is such that said plug is frictionally held in its axially adjusted position within said skirt.
